(57) **CLAIM**

The ornamental design for a construction toy piece, as shown and described.

DESCRIPTION

FIG. 1 is a top front right isometric view of the construction toy piece.

FIG. 2 is a left elevation view of the construction toy piece.

FIG. 3 is a front elevation view of the construction toy piece.

FIG. 4 is a back elevation view of the construction toy piece.

FIG. 5 is a right elevation view of the construction toy piece.

FIG. 6 is a top elevation view of the construction toy piece; and,

FIG. 7 is a bottom elevation view of the construction toy piece.

The ornamental design has tri-fold rotational symmetry.

The broken lines in the figures depict portions of the construction toy piece that form no part of the claimed design.
